UNITED STATES PATENT OFFICE.

JOHN T. LUND, OF DENVER, COLORADO.

WATER-SEAL TRAP.

No. 839,165.

Specification of Letters Patent.

Patented Dec. 25, 1905.

Application filed October 10, 1903. Serial No. 232,886.

To all whom it may concern:

Be it known that I, JOHN T. LUND, a citizen of the United States, residing in the city and county of Denver and State of Colorado, have invented certain new and useful Improvements in Water-Seal Traps; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in water-seal traps or other structures provided with a screw-cap or closure where it is desirable to form a tight joint without the aid of means other than the connected parts. In 20 traps of this character it is especially desirable that the parts provided with the screw-threads be protected from the corroding action of the contents of the trap; and to this end I have embedded a soft-metal washer or 25 ring in the cap or closure of the trap inside of the threaded flange, the top ring or portion of the trap being provided with a knife-edge adapted to engage this soft-metal ring and indent the same sufficiently to form a sealed 30 joint, whereby the contents of the trap are prevented from gaining access to the interior threads of the cap-flange or the exterior co-operating threads of the ring.

Having briefly outlined my improved construction, as well as the function it is intended to perform, I will proceed to describe the same in detail, reference being made to the accompanying drawings, in which is illustrated an embodiment thereof.

40 In the drawings, Figure 1 is a section taken through the upper part of a drum-trap equipped with my improvements. Fig. 2 is a fragmentary view showing the cap or closure detached from the trap. Fig. 3 is an elevation 45 of a drum-trap shown on a smaller scale than in Fig. 1. Fig. 4 is an ordinary S-trap to which my improvement may be applied. Fig. 5 is a fragmentary detail view illustrating a modified form of construction. Fig. 6 50 is a detail view illustrating still another form of construction.

The same reference characters indicate the same parts in all the views.

Referring first to Figs. 1, 2, and 3 of the 55 drawings, let the numeral 5 designate the body of the trap, which is usually composed

of lead. This body portion of the trap is of ordinary construction. As shown in the drawings, it is provided with the usual inlet 6, outlet 7, and vent-pipe 8. To the top of 60 the body of the trap 5 is applied a ring 9, preferably composed of brass. This ring has a shoulder 10, resting upon the upper edge of the body of the trap. The ring has a depending part 12, extending below the shoulder and engaging the body of the trap on the inside. This ring also has an upwardly-projecting part 13, exteriorly threaded, as shown at 14, to engage the interior threads of the outer flange 15 of the cap or closure 16. The 70 top of the ring part 13 is beveled to form a knife-edge 13^a, which engages a packing-ring or washer 17, preferably composed of lead run into a groove formed between the flange 15 and a short flange 18, formed on the cap. 75 The ring 9 may be secured to the body of the trap by solder 19.

In the form of construction shown in Fig. 5 the soft-metal packing-washer is inserted in a groove formed in the ring 9, the said 80 washer or packing being designated 9^a. In this view a depending flange 16^a is formed on the cap, the said flange having a sharp edge adapted to engage the washer 9^a when the cap is screwed into the closed position. This 85 construction gives substantially the same result as that obtained by the form shown in the other views.

In manufacturing the cap 6 a ring of soft metal may be pressed into the groove between the flanges 15 and 18, or the metal in liquid form may be run into the groove and allowed to harden. In any event the soft-metal ring or washer should be held securely in place. The cap is then screwed down, 90 causing the knife-edge of one part to indent the soft-metal ring or washer of the other part. If the ring 9 is to be provided with a soft-metal washer, as shown in Fig. 5, the same may be applied to the ring in the same 95 manner as above explained when speaking of the cap—that is to say, the metal ring or washer already formed may be pressed tightly into the circumferential groove of the ring, or the metal in liquid form may be run 100 into the groove and allowed to cool, as may be desired. It must be understood, however, that I do not limit the invention to any special manner of applying the soft-metal ring or washer, since it may be applied in any 105 suitable manner.

Attention is called to the fact that my im-

proved construction may be used in relations other than those heretofore explained. In other words, the edged part on one device engaging a soft-metal part on another device and means for bringing the two devices together in operative relation is believed to be novel.

The part 12 of the ring 9 may be sweated into the top of the body of the trap or secured by the use of solder, as may be desired. The application of the solder 19 is not absolutely necessary, but may be employed to give the plumber an opportunity to wipe the joint.

15 The construction shown in Fig. 4 is substantially the same in all essential features as that shown in the other views, the only difference being that the depending part 5^a of the S-trap B takes the place of the body 5 of the trap in the other views.

It may be stated that in my improved construction it is comparatively easy to unscrew the cap, because there is but little friction between the edged part and the soft-metal part, due to the fact that the surface engagement of the two parts is very slight.

25 In Fig. 6 I have shown the ring 9 with two separated edges (designated 9^c.) It may, under some circumstances, be advisable to provide the edged member with two edges, as shown in this view. In this event both

edges would engage the soft-metal ring or washer 17. This would give additional security against the possible leakage of gas or liquid.

Having thus described my invention, what I claim is—

In a drum-trap, the combination with the body of the trap, a ring having a collar adapted to engage the edge of the body of the trap surrounding the opening in the latter, the ring also having parts extending beyond the collar in both directions, one part entering the body of the trap while the other part projects beyond the same and is exteriorly threaded and provided with a knife-edge at its free extremity, and a cap having inner and outer concentric flanges, the outer flange being interiorly threaded to coöperate with the exterior threads formed on the ring, the cap being provided with a packing of soft metal run into the groove between the concentric flanges, the said packing being adapted to engage the knife-edge of the ring for the purpose set forth.

55 In testimony whereof I affix my signature in presence of two witnesses.

JOHN T. LUND.
